UNITED STATES PATENT OFFICE.

STEPHEN B. MORSS, OF RAHWAY, NEW JERSEY.

SASH-HOLDER.

SPECIFICATION forming part of Letters Patent No. 481,622, dated August 30, 1892.

Application filed May 28, 1891. Serial No. 394,386. (No model.)

To all whom it may concern:

Be it known that I, STEPHEN B. MORSS, a citizen of the United States, and a resident of Rahway, in the county of Union and State of New Jersey, have invented certain new and useful Improvements in Guides for Windows, &c., of which the following is a specification.

The object of my invention is to provide an improved guide for window-sashes, screens, and similarly-sliding bars, whereby they will be held from rattling and when the wood-work swells it will not bind on the guide, as is the case with ordinary sash or window-screen guides.

15 The invention consists in the novel details of improvement and the combinations of parts, that will be more fully hereinafter set forth, and then pointed out in the claims.

Reference is to be had to the accompanying drawings, forming part hereof, wherein—

Figure 1 is a horizontal sectional view of a window frame and sash, showing my improvement between the upper and lower sash; and Fig. 2 is a perspective view of the double 25 guide.

In the drawings the letter A indicates a window-sash, and B is the framework of a window of suitable construction.

D is my improved guide or tongue, which 30 when made as in Fig. 2 is adapted to pass between the upper and lower window-sashes. The guide or tongue D is composed of a base part d, an outwardly-projecting rib or web e, and a reversely-projecting rib or web f, connected with the rib e, said ribs having a space 35 between their sides, as shown. The ribs e and f together preferably form an acute angle or less than an obtuse angle, while the web e and the base part d preferably form a 40 right angle.

On each side of the base d are ribs e f and e f, whereby a double guide having a central space between the ribs e e is formed. This guide or tongue is made of thin metal 45 and may be rolled into the desired shape. It can be made of a single piece of metal; but of course the parts could be made separate and joined together, if desired. By placing the parts d, e, and f of the guide D at suitable angles to each other the guide will have a spring-tension. This guide is adapted to

be secured to the framing of the window-casing and to extend along the side of the sash, as shown. The base part d of the guide D may have holes to receive screws to secure it to the framing of the window. When the wood of the window-sash swells from moisture, &c., the ribs e and f in engagement therewith will contract correspondingly on account of their spring-tension, and thereby 55 binding of the sash in its guide will be overcome.

This device will be specially useful in car-windows which, as now constructed, either rattle when the car is in motion or become 60 difficult to raise or lower during wet weather on account of the swelling of the wood.

My improvement is also particularly adapted for use with window-screens, which are often made of soft cheap wood that easily 65 swells when moist. By this means easy working of the screen is always insured and the guide D can be readily put in place and removed. The length of the guide D can be varied as desired.

I find it desirable to place a strip of, say, wood D² between the ribs e e to prevent them from being bent together under extraordinary strains. With this arrangement the guide D may be placed between the upper 70 and lower sashes in position similarly to the ordinary wooden strip, each web f bearing against the side of a sash, the spring-tension of the webs f holding the sash firmly, yet allowing the latter to move freely. If 75 either sash swells, its corresponding web f will give to allow the expansion, yet always holding the sash firmly. Of course the double guide D can be placed between the sash and screen, if desired.

Having now described my invention, what I claim is—

1. As a new article of manufacture, a flexible guide for window-sashes, screens, and the like, consisting of a base d, ribs or webs e, extending outwardly from the base and having a space between them, and webs f f, extending from the webs e outwardly and backwardly at an angle to webs e, said guide being adapted to fit between sashes and its opposite webs f to bear on the opposite sashes.
2. A flexible guide composed of a base d,

ribs *e*, extending outwardly from the base and having a space between them and ribs *f*, extending backwardly from the ribs *e*, the corresponding ribs *e* and *f* forming an angle between their sides, combined with a strip *D*² fitting between the ribs *e e*.
5 Signed at New York, in the county of New

York and State of New York, this 26th day of May, A. D. 1891.

STEPHEN B. MORSS.
